(57) **CLAIM**

The ornamental design for a foldable high precision food thermometer, as shown and described.

DESCRIPTION

FIG. 1 is a front view of a foldable high precision food thermometer, showing our new design;

FIG. 2 is a rear view thereof;

FIG. 3 is a left view thereof;

FIG. 4 is a right view thereof;

FIG. 5 is an enlarged top view thereof;

FIG. 6 is an enlarged bottom view thereof;

FIG. 7 is a first perspective view thereof showing the food thermometer is folded; and,

FIG. 8 is a second perspective view thereof showing the food thermometer is unfolded.
